CONTAINER

Gladys P. Hayn, Buffalo, N. Y.

Application March 4, 1942, Serial No. 433,272

2 Claims. (Cl. 312—43)

This invention relates to improvements in containers for articles such as paper sheets, disks, cups and the like, and from which the articles may be readily dispensed or withdrawn one at a time.

One of the objects of this invention is to provide a container of this type of improved construction, in which the articles are protected from damage and supported in position to be readily removable through an opening in the side of the container. Another object of this invention is to provide a container of this type having a slot in a side thereof through which a finger may be inserted for withdrawing an article and having a top which is also provided with a slot extending inwardly from an edge thereof, and which may be placed so as to form a continuation of the slot in the container, to facilitate withdrawal of articles from the container without removing the lid therefrom. Other objects of this invention will appear from the following description and claims.

In the accompanying drawing:

Fig. 1 is a front elevation of a container embodying this invention and having a stack of articles therein.

Fig. 2 is a fragmentary sectional elevation thereof, the section being taken approximately on line 2—2, Fig. 1.

Fig. 3 is a sectional plan view thereof, on line 3—3, Fig. 1.

My improved container is particularly adapted for use in connection with readily flexible paper articles which may be in the form of sheets, disks, cups, or the like. By way of example, I have shown in the drawing articles 5 which are in the form of flexible paper cups, such as frequently used as cups for candies, bonbons, and the like, these cups being provided with radial corrugations 6 which extend from the outer edges of the cups to the middle flat portion. It is not intended, however, to limit this invention to use in connection with paper cups of this type, since my improved container may be used in connection with flat disks or sheets of readily flexible material.

My improved container comprises a body portion 8 which may be of any suitable or desired shape, the cross sectional shape of the container preferably being such as to readily receive the articles 5 arranged in an upright stack. In the particular construction illustrated, the body portion 8 of the container is of cylindrical form and has a bottom 9, which is preferably rounded or

of dished form, and which supports the stack of articles in the container.

The body portion 8 of the container is provided with a longitudinal opening or slot 10 in a side thereof, this opening extending substantially throughout the height of the container and also at least partly into the bottom 9 thereof from the outer edge toward and, if desired, beyond the middle portion of the bottom. This slot or opening 10 is made large enough to permit a finger to be inserted therethrough into the container for the purpose of grasping the uppermost article 5. Since these articles are made of relatively thin paper or other material and are readily flexible, they can be flexed or deformed into such shape that they may be readily withdrawn through the opening or slot 10. In Fig. 3, one of the articles is shown in dotted lines in the slot or opening while being withdrawn from the container.

20 The container is provided with a lid or cover 12 which is made of such form as to be readily placed upon and removed from the upper end of the container and held in engagement thereby, for example, by having the side edges 14 thereof telescope about the upper end of the container. In order to facilitate the removal of articles from the container when the stack substantially fills the container, it is also desirable to provide the lid or cover 12 with a slot or opening 15 extending from an edge of the container toward or beyond the middle portion thereof, and this slot is preferably of approximately the same width as the slot 10 of the body portion of the container and the cover is preferably arranged on the container so that the slot therein forms substantially a continuation of the slot in the body portion of the container as shown in Fig. 1.

Any suitable or desired means may be employed for supporting the container in substantially upright position. This may, for example, be accomplished by providing the rear wall of the body portion 8 of the container with a hole or opening 17 which may, if desired, be of the key-hole slot type, and which may cooperate with a nail or other support to permit the container to be suspended therefrom. The container may be made of any suitable or desired materials, such for example as molded plastic compositions, cardboard, sheet metal or wood.

50 My improved container may be used for any desired purpose to facilitate the storing and removal of flexible sheets of articles therefrom. For example in packaging candies, the container may receive a stack of cups such as illustrated in the drawing. These cups can then be readily re-

moved one at a time from the top of the stack by inserting the index finger through either of the slots 10 or 15 and placing it on the top surface of the uppermost article. The thumb may be used to hold back the lower articles of the stack and to grasp the lower edge portion of the upper article which is being removed. The article may then be pulled out through the slot 10 or 15, and this action of removing the articles one at a time can be effected with great speed, since the walls of the container adjacent to the slot tend to resist withdrawing of other articles than the uppermost one.

My improved container may also be used in kitchens, since flexible articles such as paper disks, cups, or the like are very useful in the handling of materials in kitchens. For example, if it is desired to grease a pieplate or cake dish, these flexible cups or sheets may be used for removing the lard, butter, or other material employed for this purpose from a container or mass of the material and this material may then be applied to a pan or plate for greasing the same without having the material come in contact with the hand.

The top of the container is readily removable so that one or more sheets or articles may be placed into the container.

By making the bottom of the container of rounded or dished shape, a stack of candy cups will be readily supported in their normal positions in the container. If the container is used in connection with the dispensing of flat sheets or disks, the dished form of the bottom facilitates removal of the sheets from the stack since the middle portions of the sheets may be depressed by the finger inserted through the slot, so that the edge of the uppermost sheet can be more readily grasped between the thumb and finger for removing it from the stack. If desired, however, the bottom of the container may be of flat or other shape.

I claim:

1. A container for readily flexible articles, said container having a body portion formed to receive a stack of said articles, a bottom on which said articles rest and which is of downwardly dished form, a lid for the top of said container, said body portion having an upright slot in a side thereof and said bottom having a slot forming a continuation of said slot of said body portion and extending inwardly from the edge of said bottom, said lid of said container having a slot therein of substantially the same width as the slot in said body portion and extending inwardly from an edge of said lid, and forming substantially a continuation of the slot in said body portion, said slots in said body portion and said lid being of sufficient width to permit the insertion of a finger therethrough for grasping the uppermost article of said stack.

2. A container for readily flexible cupped paper disks, said container having a substantially cylindrical hollow body portion having an internal diameter slightly greater than the diameter of the disks to receive a stack of said disks, a bottom on which said stack of disks rests, said body portion having an upright slot therein of substantially the same width throughout its length and extending substantially throughout the height thereof and of sufficient width to permit the insertion of a finger to withdraw the disks one at a time through said slot from the top of the stack but of materially less width than the width of the flexible disks, and a removable lid for said container arranged to rest on the top of said body portion and having a substantially radial slot therein of approximately the width of said slot in said body portion and which, when said lid is placed in correct relation to said body portion, forms a continuation of said slot of said body portion, to permit placing a finger upon the top of the uppermost disk, said disks being partly folded about their middle portions when passing through said slot of said body portion.

GLADYS P. HAYN.
